UNITED STATES PATENT OFFICE

SCREW DRIVER

Peter L. Robertson, Milton, Ontario, Canada

Application September 20, 1944, Serial No. 554,973

1 Claim.

(Cl. 145—50)

2

The invention relates to improvements in screw drivers and particularly to a type of screw driver adapted for use in driving socket or recessed headed screws and the principle object of the invention is to provide a tool which will have bits providing a variety of points or tips to fit various sizes of socket screws readily available for the workman with the least possible expenditure of time.

A further object is to devise an inexpensive tool structure of extremely simple and accurate construction in which removable or exchangeable bits will be rigidly held for operative use and may be easily and quickly released and removed.

The principal feature of the invention consists in devising a structure in which bits of angular cross section are adjustably and removably mounted in a tubular shank and are securely held from rotation by engagement of their angular adjacent faces extending into longitudinal slots formed in the tubular shank and are rigidly secured by a constricting chuck mounted upon the slotted tube.

In the accompanying drawing Figure 1 is an elevational view of a screw driver constructed in accordance with the present invention.

Figure 2 is an enlarged longitudinal mid-sectional view of a portion of the tubular bit-holding member of the screw driver illustrated in Figure 1.

Figure 3 is an end elevational view of the driver shown in Figure 2.

Figure 4 is a cross section through the driver taken on the line 4—4 of Figure 2.

Figure 5 is an elevational detail of one type of dual purpose bit.

Figure 6 is an end view of the bit shown in Figure 5.

Figures 7, 8 and 9 are elevational views of screw drivers constructed similar to Figure 1 having different forms of shank ends for engagement with standard driver handles or tools.

Figure 10 is a longitudinal sectional view of a short type of screw driver constructed in accordance with this invention.

Several sizes of socket head screws are obtainable in the open market and it is well known that the dimensions of the sockets vary in accordance with the sizes of the screws. These socket sizes are usually divided into three sizes and normally it is necessary for a workman to be provided with screw drivers of three separate sizes in order that he may handle the various sizes of screws which he may encounter in the course of his work.

It will be readily understood that such conditions will result in much loss of time in locating the proper sized driver and frequently one or other of such drivers may be mislaid and much inconvenience results.

It is extremely desirable that a workman be provided with a tool which will enable him to have

all sizes of bits that may be required readily available so that he may quickly change from one to the other and which will hold the bits rigidly so that his work may not be impaired.

In carrying this invention into effect I construct the driver bits 1 from parallel multi-faced steel preferably of square cross section and the ends of such bits are shaped with socket fitting tips 2, 3 and 4 of dimensions suitable for the screw sockets which will be encountered.

Bits are also preferably formed with flat tips 5 adapted to enter the slots of ordinary slotted screws.

It will be seen on reference to Figure 2 that two bits will provide four different sizes and kinds of tips, and both bits are formed of stock square in cross section, and preferably of the dimensions of the largest type of square socket screw. The bit end 5 is bevelled angularly from two corners so that it presents a flat tip across the diagonal dimension of the bit stock. This arrangement permits its use in a slot type screw and the angled corners will fit into the corners of a square socket screw.

The second bit with which a driver is equipped is formed with the reduced ends 3 and 4 to fit other sizes of sockets.

The shank 6 of the driver is made from tubular stock, one end of which is bedded in the handle 7 and the outer end is formed with a threaded portion 8 adjacent to the extremity upon which a chuck collar 9 is threaded.

The tubular member 6 is preferably slightly reduced in diameter beyond the threaded portion 8 and has a bevelled surface 10 which is engaged by a bevelled surface 11 on the inner wall of the collar 9.

The tube 6 is preferably slotted with diagonal cross slots 12 which extend longitudinally for a length approximately the length of two of the bits and the angled longitudinal corners of the bits enter and slide longitudinally in the said slots.

The tubular shank is reamed for a distance 45 slightly past the inner ends of the slots 12 and a shoulder 13 is thus formed.

A cylindrical block 14 slidable within the reamed bore of the tubular shank is adapted to engage the shoulder 13 and forms an anvil against which the inner of the bits inserted into the slotted shank engages.

A collar 15 slidably encircling the tubular shank is connected to the anvil block 14 by a cross pin 16 extending through one of the slots and with said block forms an ejector for removing the bits from the shank.

It will be understood that when the angle-faced bits are slipped into the slotted shank with their longitudinal corners entering the longitudinal slots, the slot edges form sliding guide surfaces

and upon the tightening of the chuck collar 9 against the bevel surfaces adjacent to the outer end of the shank, the slot edges will be pressed into tight gripping contact with the sides of the bit. This gripping is not however depended upon to take the full working thrust of the screw driver, as the anvil block, bedded against the shoulder 13 in the shank forms a solid abutment to take the thrust. 5

The tool thus described provides bits with all 10 desired sizes of tips and in order to change from one to another it is merely necessary to loosen the chuck collar then push against the collar 15 moving the anvil block to push the bits outwardly. The desired tip is then selected and the bits 15 returned to the tubular shank in the proper position and upon tightening the chuck collar it is again ready for use.

In certain types of drivers where short length is required, such as is shown in Figure 10, the 20 collar 13 with its cross pin through the anvil block may be dispensed with. In such construction the anvil block may be made a tight fit in the reamed end of the tube and when pressed in against the shoulder 13 it will remain fixed and 25 provides a solid anvil surface in the tubular shank to receive the end thrust against the bit.

Figures 7, 8 and 9 illustrate the application of this invention to various types of shank ends that are used to fit various commercial tools such as a "Yankee" driver, an electric driver or an ordinary "brace" driver.

The adaptation of a tubular shank enables a driver being made with a "well" or recess in which any desired number of bits may be housed 35 so that they will be readily available.

It will be readily understood that while bits of square cross section are shown other angular cross section shapes may be used to the same advantage. Also the bits shown are adapted for 40 square socket screws but the bits may be made of other shapes to fit other sockets such as crossed slot sockets or sockets of other forms.

A tool such as described is of extremely practical value and is neat and easy to handle. 45

What I claim as my invention is:

A screwdriver comprising a tubular shank having an enlarged bore extending inwardly from one end thereof and defining an annular shoulder and, having longitudinal slots arranged in diametrically opposite pairs extending inwardly from said end, a plurality of bits of square cross section arranged in axial end-to-end engagement in said shank and presenting longitudinal edges engaging in said slots maintaining said bits against rotation, an anvil block slidably arranged in said shank and engaging the inner end of the innermost of said bits, means to operate said anvil block to advance all of said bits toward the operating end of said tubular shank to adjustably expose the outermost of said bits, and means to lock the outermost of said bits from movement longitudinally of said shank in adjusted exposed position, said anvil block when retracted engaging said shoulder to receive through said bits arranged in end-to-end relation, the thrust against the outermost bit.
